UNITED STATES PATENT OFFICE.

BIAGIO NERO, OF CLEVELAND, OHIO.

DRIVEWAY-PAVING BLOCK.

1,202,410.

Specification of Letters Patent. Patented Oct. 24, 1916.

Application filed July 17, 1916. Serial No. 109,732.

To all whom it may concern:

Be it known that I, BIAGIO NERO, a subject of the King of Italy, residing at Cleveland, in the county of Cuyahoga and State of Ohio, have invented certain new and useful Improvements in Driveway-Paving Blocks, of which the following is a specification.

This invention relates to paving or paving blocks, and has for its object to provide an improved block especially adapted and intended for use in the construction of a roadway for motor vehicles. These roadways are commonly or often laid across lawns, as from the street to the garage. By means of the present invention the blocks can be laid to form such a roadway without extensive excavation or preparation, and the edges of the roadway may be set flush with the ground surface, so as to not interfere with the operation of a lawn mower or the like, two tracks of good appearance being produced, and the use of blocks permitting their manufacture in quantities, and avoiding the delays and the inconveniences incident to molding the tracks in the permanent position, the blocks being supplied in such quantities as may be necessary, and laid at once in final position.

30 A further feature of the invention is the provision or means for connecting adjacent blocks to hold them in line and prevent accidental displacement.

The invention is illustrated in the accompanying drawing which is a perspective view of a roadway made of the blocks.

Each block comprises a base 6 with upwardly projecting flanges or sides 7, forming a channel which serves to confine and 40 guide the wheels of a vehicle. The height of the flanges 7 may be varied as desired, to make the channel or track of greater or lesser depth. Ordinarily a depth of an inch or two will be sufficient for the intended 45 purpose, and the blocks are symmetrically

constructed so that they will match at either end. Each block is preferably provided with reinforcing bars 8 extending lengthwise therein and conveniently located adjacent the lower outer corners of the block. 50 At one end, these bars project a short distance beyond the end of the block, as indicated at 9, and the other end of the block has corresponding recesses 10, so that when the blocks are laid the projecting ends 9 of 55 one block will fit in the recesses 10 of the next block and lap the joint, thereby holding the blocks permanently in line and in proper position. Cement may also be applied between the ends of the blocks if desired. 60

In constructing the roadway it is necessary only to cut a trough in the lawn or ground and set the blocks therein, with their upper edges flush with the surfaces, and the 65 roadway is ready for use at once. No forms are required at the place, since the blocks may be molded in quantities at the factory. The dirt and delay, and injury of lawns, incident to ordinary cement working is 70 thereby avoided, and the blocks can be laid by unskilled persons.

What I claim as new is:

A concrete block having side flanges projecting upwardly at opposite edges thereof, 75 forming a channel extending along its upper surface and provided with longitudinal metal reinforcing bars embedded in the lower outer corners thereof, at the base of said flanges, said bars projecting at one end, 80 and the opposite end of the block having recesses adapted to receive the projecting ends of the bars of an adjacent block.

In testimony whereof, I do affix my signature in presence of two witnesses.

BIAGIO NERO.
